(57) **CLAIM**

(73) Assignee: **Biacore AB**, Uppsala (SE)

The ornamental design for a cover for a measuring cassette for biosensor apparatus, as shown and described.

(**) Term: **14 Years**

DESCRIPTION

(21) Appl. No.: **29/150,461**

FIG. 1 is a top isometric view of a cover for a measuring cassette for biosensor apparatus showing our new design, with the chip carrier shown projection therefrom;

(22) Filed: **Nov. 15, 2001**

FIG. 2 is a bottom isometric view thereof;

(30) **Foreign Application Priority Data**

FIG. 3 is a top isometric view thereof, with the chip carrier shown within the cover;

May 16, 2001 (SE) 01-0869

FIG. 4 is a bottom isometric view thereof;

(51) LOC (7) Cl. **24-02**

FIG. 5 is a top isometric view thereof;

(52) U.S. Cl. **D24/224**; D24/216

FIG. 6 is a bottom isometric view thereof;

(58) **Field of Search** D24/216, 224,

FIG. 7 is an end view thereof;

D24/225, 227, 232, 231; D10/81; 206/569,

FIG. 8 is a top plan view thereof;

370, 362, 459.1; 422/58, 61, 56, 102; 204/403.1,

FIG. 9 is a side view thereof;

1, 403.2, 403.3, 409, 193

FIG. 10 is a bottom plan view thereof; and,

(56) **References Cited**

FIG. 11 is an end view thereof, opposite that shown in FIG. 7.

U.S. PATENT DOCUMENTS

The broken line showing of the chip carrier is for illustrative purposes only and forms no part of the claimed design.
